(57) **CLAIM**

The ornamental design for a squirt gun amusement device, as shown.

DESCRIPTION

FIG. 1 is a side elevational view of one side of a toy gun showing our new design;

FIG. 2 is a side elevational view of the other side;

FIG. 3 is a top plan view thereof;

FIG. 4 is a bottom plan view thereof;

FIG. 5 is a front elevational view thereof;

FIG. 6 is a rear elevational view thereof.

FIG. 7 is a side elevational view of one side of another embodiment of a toy gun showing our new design;

FIG. 8 is a side elevational view of the other side of the embodiment of FIG. 7;

FIG. 9 is a top plan view of the embodiment of FIG. 7;

FIG. 10 is a bottom plan view of the embodiment of FIG. 7;

FIG. 11 is a front elevational view of the embodiment of FIG. 7; and,

FIG. 12 is a rear elevational view of the embodiment of FIG. 7.

The broken lines shown in FIGS. 7-12 are for illustrative purposes only and form no part of the claimed design.
